Edgar V. Hale & Co.

UNITED STATES PATENT OFFICE.

JOHN GIGLIO, OF NEW YORK, N. Y.

PIANO-PEDAL.

1,340,162.

Specification of Letters Patent. Patented May 18, 1920.

Application filed February 28, 1919. Serial No. 279,705.

To all whom it may concern:

Be it known that I, JOHN GIGLIO, a citizen of the United States, and residing at New York, in the county of New York and 5 State of New York, have invented certain new and useful Improvements in Piano-Pedals, of which the following is a specification, such as will enable those skilled in the art to which it appertains to make and 10 use the same.

This invention relates to piano pedals and particularly to the method of mounting the same in connection with the base portion of the piano; and the object of the 15 invention is to provide a simple and inexpensive construction of the class specified whereby the pedals may be quickly attached to or detached from the piano whenever necessary for the purpose of cleaning or re- 20 pairs; and with this and other objects in view the invention consists in an apparatus of the class and for the purpose specified, constructed and operating as hereinafter described and claimed.

25 The invention is fully disclosed in the following specification, of which the accompanying drawing forms a part, in which the separate parts of my improvement are designated by suitable reference characters 30 in each of the views, and in which:

Fig. 1 is a sectional plan view of a part of the base portion of a piano and indicating my improvement in connection therewith;

35 Fig. 2 a partial section on the line 2—2 of Fig. 1;

Fig. 3 a view similar to Fig. 2 but showing only a part of the construction and on an enlarged scale and with other parts in 40 section;

Fig. 4 a partial section on the line 4—4 of Fig. 1 and on an enlarged scale and with part of the construction shown in Fig. 1 omitted;

45 Fig. 5 a detail perspective view of one of a number of springs which I employ; and,

Fig. 6 a partial section on the line 6—6 of Fig. 1 and on an enlarged scale.

In the drawing I have shown at 10 a 50 part of the base portion of a piano and comprising a bottom member 11, a back 12, sides 13, one of which is shown, and a front base board 14 having a plurality of openings 15 in the central portion thereof in 55 which a plurality of pedals 16 are mounted.

In the construction shown, I have indi-

cated three pedals, or the number of pedals usually employed in connection with a piano, and each of these pedals consist of a front foot piece 17 inwardly of which is 60 a raised lug 18 and a depending lug 19, and the inner end of the pedal is provided with a head 20 in which is mounted a pin 21, the opposite ends of which extend outwardly of the head to form trunnions 22. 65

I also employ a transverse bearing box 23, the top portion of which is provided with three spaced apertures 24 which open forwardly and backwardly through the box, as clearly shown in Figs. 2 and 3, and 70 formed in the top portion of the box at the opposite sides of each of said openings are semi-circular bearing seats 25 having felt facings 26. A cover 27 is mounted on the top of the box 23 and guided by pins 75 28 in the opposite ends of the box, which pins pass through said cover as clearly shown in Fig. 4, and said cover 27 is held in engagement with the box 23 by three bolts 29 located centrally of the rear end portion 80 of the apertures 24, and which pass through elongated apertures 30 in the cover 27, and on the upper end of which are mounted winged nuts 31 which also pass through the apertures 30 when in a position at right 85 angles to that shown in Fig. 1.

The cover 27 is provided on the bottom face thereof and in line with the semi-circular bearing seats 25 with similar bearing seats 32 which are also provided with 90 felt facings 33. These bearing faces co-operate with the bearing faces 25 to form a cylindrical bearing for the trunnions 22 on the head end 20 of the pedals 16, and the felt facings 26 and 33 form cushioned 95 noiseless supports for the trunnions of the pedals.

At the front of each of the apertures 24, the box 23 is provided with a vertical recess or aperture 34 which forms web portions 35 in the box member at the front of said aperture in connection with which the hook-shaped end 36 of a flat spring member 37 operates as shown in Figs. 2 and 3 of the drawing.

105 The bottom faces of the pedals 16 are preferably raised as shown at 38 and levers 39 are pivoted centrally thereof as shown at 40, one end of said levers being provided with downwardly directed cushion pads 41 110 and headed pins or bolts 42 are adapted to pass downwardly through the inner end

portions of the pedals and operate in connection with the other portions 43 of the levers 39 as clearly shown in Fig. 3. The springs 37, or the end portions thereof, bear 5 on the bottom portions of the pedals or the levers 39 pivoted therein, and serve to hold the pedals normally in a raised position and to raise the pedals into the normal position, after they have been depressed by the feet 10 of an operator in the usual manner and in the depression of the pedals, the cushion pads 41 on the levers 39 operate in connection with the bottom 11 of the piano to limit the downward movement of the pedals. 15 I also secure to the top central portion of each of the pedals 16 levers 44, 45 and 46, the levers 45 and 46 extending to the left, while the lever 44 extends to the right, and the free end portions 20 of the levers 45 and 46 are provided with arms 47 and 48 which operate in connection with vertical rods 49 and 50 secured to the free ends thereof in the usual manner. The levers 45 and 46 are pivoted approximately 25 centrally thereof in a pivot block 51 having two compartments 52 and 53 adapted to receive each of said levers and springs similar to the springs 37 are held in connection with the block 51 or the compartments 52 and 53 30 by the engagement of the hook end 36 of said springs with upwardly directed V-shaped portions 54 and transverse pins 55 in the bottom portion of the compartments in said block. The levers 45—46 are held 35 in engagement with the block 51 by a transverse pin 56 which operates in V-shaped portions 57 in the top faces of said levers while other V-shaped portions 58 in the bottom faces of said levers operate in connection 40 with the upwardly directed V-shaped portions 54 in the block 51, or the hook ends 36 of the springs. The construction and method of mounting one of the levers in connection with the pivot block 51 is clearly 45 indicated in Fig. 6 of the drawing, and it will be noted that the springs 37 operate to hold the inner end portions of the levers 45—46 in a raised position.

In the accompanying drawing I have 50 shown the pedals in their operative position, or connected with the box member 23, and when it is desired to detach said pedals from the box for the purpose of cleaning and making repairs or otherwise, the winged 55 nuts 31 are first turned into a position at right angles to that shown in Fig. 1, after which the cover 27 is detached from the top portion of the box 23, in which operation the nuts 31 pass through the elongated apertures 30.

The head end 20 of the pedals 16 may then be removed from the bearing seats 25 in the box member 23, after which the springs 37 may be removed, if desired.

65 From the foregoing it will be readily un-

derstood that with my improved method of mounting pedals in connection with a piano, the pedals may be readily attached and detached whenever desired and with little or no labor, or loss of time, and while I have 70 shown certain details of construction for carrying my invention into effect, it will be understood that I am not limited to these details, and various changes therein and modifications thereof may be made, within 75 the scope of the appended claims, without departing from the spirit of my invention or sacrificing its advantages.

Having fully described my invention, what I claim as new and desire to secure 80 by Letters Patent, is:—

1. In a piano, a pedal, a bearing member, the inner end portion of the pedal being rotatably mounted in the bearing member, 85 a spring mounted in the bearing member and operating in connection with the protruding portion of the pedal, means for retaining the inner end portion of the pedal within the bearing member, and a lever pivotally and adjustably mounted in the bottom 90 central portion of the pedal and arranged longitudinally thereof.

2. In a piano, a pedal, a bearing member, the inner end portion of the pedal being rotatably mounted in the bearing member, 95 a spring mounted in the bearing member and operating in connection with the protruding portion of the pedal, means for retaining the inner end portion of the pedal within the bearing member, a lever pivotally and adjustably mounted in the bottom 100 central portion of the pedal and arranged longitudinally thereof, and another lever pivotally mounted in the piano and one end of which is secured to said pedal. 105

3. In a piano, a pedal, a bearing member, the inner end portion of the pedal being rotatably mounted in the bearing member, a spring mounted in the bearing member and operating in connection with the protruding portion of the pedal, means for retaining the inner end portion of the pedal within the bearing member, a lever pivotally and adjustably mounted in the bottom 110 central portion of the pedal and arranged longitudinally thereof, another lever pivotally mounted in the piano and one end of which is secured to said pedal, and tensional means for operating said last named lever in one direction. 115

4. A pedal support and bearing member for pianos, comprising a box-shaped member composed of top and bottom parts, bearing faces formed between the separate parts of the box member and in which the inner 125 end portions of a plurality of pedals are adapted to be mounted, means for securing the separate parts of the box member together to retain the inner end portions of said pedals therein, fibrous facings for the 130

bearing faces in the separate parts of the box member, and tensional devices detachably mounted in the bottom part of the box-shaped member and adapted to operate 5 in connection with said pedals.

5. A pedal support and bearing member for pianos, comprising a box-shaped member composed of top and bottom parts, the abutting faces of said parts being provided 10 with a plurality of correspondingly arranged apertures and with a plurality of bearing faces at the opposite sides of said apertures, a plurality of pedals provided at their inner ends with oppositely directed 15 trunnions adapted to be mounted in the bearing faces of the separate parts of the box-shaped member, means for securing the separate parts of the box-shaped member together to retain the pedals therein, and 20 spring devices detachably connected with the bottom part of the box-shaped member and adapted to operate in connection with said pedals to normally hold the same in a raised position.

25. 6. A pedal support and bearing member for pianos, comprising a box-shaped member composed of top and bottom parts, the abutting faces of said parts being provided with a plurality of correspondingly arranged apertures and with a plurality of bearing faces at the opposite sides of said 30 apertures, a plurality of pedals provided at their inner ends with oppositely directed trunnions adapted to be mounted in the bearing faces of the separate parts of the box-shaped member, means for securing the 35 separate parts of the box-shaped member together to retain the pedals therein, a plurality of spring devices hook-shaped in form 40 at one end to permit of their connection

with the bottom part of said box-shaped member beneath the pedals mounted therein, and levers mounted longitudinally of said pedals and in connection with which the free ends of said spring devices are adapted 45 to operate to hold the pedals normally in a raised position.

7. A pedal support and bearing member for pianos, comprising a box-shaped member composed of top and bottom parts, the 50 abutting faces of said parts being provided with a plurality of correspondingly arranged apertures and with a plurality of bearing faces at the opposite sides of said 55 apertures, a plurality of pedals provided at their inner ends with oppositely directed trunnions adapted to be mounted in the bearing faces of the separate parts of the box-shaped member, means for securing the separate parts of the box-shaped member together to 60 retain the pedals therein, a plurality of spring devices hook-shaped in form at one end to permit of their connection with the bottom part of said box-shaped member beneath the pedals mounted therein, levers 65 mounted longitudinally of said pedals and in connection with which the free ends of said spring devices are adapted to operate to hold the pedals normally in a raised position, and means operating in connection 70 with one end portion of said levers for adjusting the position thereof.

In testimony that I claim the foregoing as my invention I have signed my name in presence of the subscribing witnesses this 75 26th day of February, 1919.

JOHN GIGLIO.
